UNITED STATES PATENT OFFICE.

JERVIS BENNETT WEBB, OF MOUNT VERNON, NEW YORK, ASSIGNOR TO H. W. JOHNS-
MANVILLE COMPANY, A CORPORATION OF NEW YORK.

FURRING-STRIP.

1,193,092.

Specification of Letters Patent.

Patented Aug. 1, 1916.

Application filed October 24, 1914. Serial No. 868,513.

To all whom it may concern:

Be it known that I, JERVIS BENNETT WEBB, a citizen of the United States of America, residing at Mount Vernon, county 5 of Westchester, State of New York, have invented certain new and useful Improvements in Furring-Strips, of which the following is a specification.

My invention relates generally to coverings for walls and ceilings and has particular reference to means for uniting, stretching and securing any required number of widths of the covering fabric in position on a wall or ceiling in a manner to present a 15 continuous surface, uniformly smooth and even throughout its entire area and broken only by seam-line effects, such as would ordinarily be produced by sewing, at the meeting edges of the several widths of fabric 20 which go to make up the covering.

While the invention is adaptable for various purposes, it finds its principal use in acoustical construction, where fabrics, applied as a covering for felt and like material, are required to be stretched smoothly 25 over large surfaces or panels in which no molding is to appear.

The covering fabric, applied in accordance with the present invention, serves to 30 entirely conceal the means employed to secure it in position. This arrangement enables surfaces of unlimited area to be covered without in any way sacrificing the appearance of the covering by requiring the 35 use of finishing strips at intermediate points throughout a panel and at the same time gives rise to an important advantage in that it permits whatever reinforcement may be necessary to insure solid construction.

Another important feature of the present 40 invention consists in supporting that portion of the fabric forming the covering proper, out of contact relation with both the surface covered and the means employed 45 to unite and secure the several widths of fabric thereon. In thus supporting the covering proper free and clear of the wall or ceiling, all surface inequalities are avoided, as well as discoloration from uneven fading 50 of the shade or color of the fabric and the collection of dust in sections or portions thereof.

The accompanying sheet of drawings illustrates the best form of device at present

known to me for carrying my invention into 55 effect.

In the drawings, Figure 1 is a sectional view illustrating the method of applying covering fabric to a wall or like surface, in accordance with the present invention; Fig. 60 2 is a detailed sectional view showing the preferred form of two-part strip herein employed for uniting and securing widths of covering fabric to a wall or like surface, the strip members being shown in separated 65 relation, ready to engage the overlapping edges of adjoining widths of the covering extending between them, and Fig. 3 is a similar view of a finished portion of the covering, showing two widths of fabric 70 united and secured in position by the two-part strip.

Referring now to the drawings, throughout the several views of which like reference characters indicate like parts, I have 75 represented at 1, for convenience of illustration, a conventional showing of a wall, ceiling or similar surface, the detail construction of which is unimportant herein as the present invention resides wholly in 80 the wall covering and the manner of applying it to the surface thereof, which latter is indicated by the line 2.

Ordinarily, the covering, as applied to walls or ceilings, is in the form of panels, 85 each of which usually requires a number of widths of fabric to cover it and as it is desirable for many reasons, and often necessary, in meeting the requirements of specifications, to avoid the use of molding or finishing strips, excepting around the edge of panels, means must be provided at intermediate points for presentably uniting the several widths of covering and securing them to the wall in a manner to insure solid 90 construction and avoid objectionable surface inequalities.

A device suitable for meeting the above requirements is shown in the drawings as a two-part strip, one member 3, of which is 100 adapted to be secured to the wall by screws 4, or other fastenings and is grooved throughout its length, as at 5, to receive the other member 6, which is in the form of a tongue, shaped to enter and fit snugly with- 105 in the groove. The member 3, is cut away or beveled in opposite directions, as indicated at 7 and 8, from the point 9, at one

2
side of the groove therein, giving its surface an approximate V-shape in cross section and the tongue member 6, is suitably shaped, as at 10, to conform to the bevel, 5 as is clearly shown in Fig. 3.

In the use of the device, a number of the grooved strip members 3, the length of the panel, are arranged in parallel relation, on centers from two to eight feet, throughout 10 the area to be covered and fastened to the wall. A width of fabric, such as is indicated for example, at 11, in Fig. 2, is then suitably secured along one edge to the right hand marginal strip (not shown) of the 15 panel and after being well drawn over the first grooved strip member 3, has its opposite edge firmly tacked to the beveled surface 8, thereof. A second width of fabric, indicated at 12, in Fig. 2, is then arranged 20 face down on the first width 11, and its edge secured in like manner to the beveled surface 8, of the strip 3. Next the tongue member 6, is placed on the overlapping edges of the two widths of covering fabric immediately 25 over the groove (see Fig. 2) and on being pressed or forced inward, carries both thicknesses of material with it into the groove, as shown in Fig. 3, where it is secured by screws, nails or the like 13. As a 30 result of causing the overlapping edges of both widths of covering fabric to be carried into the groove by the tongue, they become securely united along the line of such overlapping edges, and at the same time, the 35 width 11, is subjected to a further stretching action which takes up any remaining fullness and draws the fabric sufficiently to free it of wrinkles and give it a perfectly smooth and even surface. The width 12, is 40 then folded over, drawn to the second grooved strip and its free edge tacked fast, as before, to the beveled surface 8, thereof. On reaching this point in applying the covering, it will be observed that the two-part 45 strip employed to unite and secure the widths 11, and 12, to the wall along the line of their meeting edges, will be entirely concealed by the covering, and as arranged, will lie wholly below that portion of the fabric 50 forming the covering proper, the inturned edges only of the fabric being engaged owing to the beveled form given the strip. Exteriorly, the effect at the meeting edges of the two widths of fabric is similar in all 55 respects to a finished seam produced by a line of stitching. Continuing to apply the covering, the third width is placed and secured in precisely the same manner as the second above described and so on throughout 60 the panel or other surface to be covered, as represented in Fig. 1. The addition of suitable marginal finishing strips or moldings completes the work.

As the many important advantages of the 65 invention will be apparent to those skilled

in the art, it is not deemed necessary to further enlarge upon the brief statement of the same contained in the foregoing description.

It will be understood, that I do not limit myself to the exact form or details of the 70 two-part strip herein shown and described, as various changes may be made therein without departing from the spirit and scope of my invention. Strips of different shape in cross section may be employed and as 75sembled in other relations than that shown, provided they serve to unite and secure two widths of covering fabric in position and are concealed by such widths. Other means capable of performing the same or substantially the same function, may be substituted for the tongue and groove features of the strip. The strip members may be constructed of any desired material and given either solid, skeleton or other form. Any suitable 80 means may be employed for securing the strip members operatively assembled and various other modifications made, which have not been illustrated, as all such changes I 85 consider to be clearly within the present invention.

Having, therefore, described my invention, I claim:—

1. In coverings for walls and ceilings, means securing two widths of covering to 95 the wall or ceiling along the line of their adjoining edges, the said means being concealed by the covering and having contact relation with the meeting edges only thereof in the rear of the outer surface of the covering.

2. In coverings for walls and ceilings, a plurality of widths of covering arranged with their adjoining edges overlapping, and means uniting and securing the several 105 widths of covering to the wall or ceiling along the lines of their overlapping edges, the said means being concealed by the covering.

3. In coverings for walls and ceilings, two 110 widths of covering material arranged with their adjoining edges overlapping, and a two-part fastening means adapted to unite and secure the widths of covering to the wall or ceiling along the line of the overlapping 115 edges, one member of the fastening means having the said overlapping edges secured to it and the other member being concealed within a fold of the covering.

4. In coverings for walls and ceilings, two widths of covering material arranged with their adjoining edges overlapping, and tongue and grooved members adapted to unite and secure the widths of covering to the wall or ceiling along the line of their 125 overlapping edges, the grooved member having the said overlapping edges fastened to it and both widths of material extending under the tongue member in the groove thereof.

5. In coverings for walls and ceilings, two 130

widths of covering material arranged with their adjoining edges overlapping, and tongue and grooved members adapted to unite and secure the widths of covering to the wall or ceiling along the line of their overlapping edges, the grooved member having the said overlapping edges fastened to it and both widths of material extending under the tongue member in the groove thereof, the said members being concealed by the covering and shaped to clear that portion thereof lying in a plane parallel with the wall or ceiling.

6. In coverings for walls and ceilings, two widths of covering material arranged with the meeting edges thereof turned inward, and means secured to the wall or ceiling engaging the said inturned edges, the said means being shaped to clear that portion of the material forming the covering proper.

7. A fastening means for securing sheets of flexible sound absorbing material to a wall or ceiling comprising in combination a strip adapted to be affixed to the wall or ceiling and having a groove in its outer surface, and a second strip fitting into said groove, adapted to clamp the meeting edges of the sheets therein, and shaped so as to be flush with an outer surface of the fixed strip when in such clamping position, the outer faces of both said strips being so shaped that when assembled the cross sectional profile of the structure is V-shaped.

8. A fastening means for securing sheets of flexible sound absorbing material to a wall or ceiling comprising in combination a strip adapted to be affixed to the wall or ceiling and having a groove in its outer surface, and a second strip fitting into said groove, adapted to clamp the meeting edges of the sheets therein, and shaped so as to be flush with an outer surface of the fixed strip when in such clamping position, the outer faces of both said strips being so shaped that when assembled the cross sectional pro-

file of the structure is V-shaped, the apex of the V projecting outwardly and coinciding with one of the lines of meeting of the two strips' outer surfaces.

9. A sound absorbing covering for walls and ceilings comprising in combination a series of strips adapted to be fastened to the wall or ceiling and project outwardly therefrom, a series of flexible sheets of sound absorbing material having their meeting edges folded together, and means for attaching said folded portions of the sheets to the exterior, projecting faces of the strips, said fastening means being concealed behind non-folded portions of the sheets.

10. A sound absorbing covering for walls and ceilings comprising in combination a series of strips adapted to be fastened to the wall or ceiling and project outwardly therefrom, a series of flexible sheets of sound absorbing material having their meeting edges folded together, and means for attaching said folded portions of the sheets to the exterior, projecting faces of the strips, said fastening means being concealed behind non-folded portions of the sheets, the exterior faces of the strips being V-shaped in cross section, and the meeting edges of the non-folded portions of the sheets resting on the apices of the V-shaped strip faces.

11. A fastening for securing sheets of flexible material to a wall or ceiling comprising the combination of a strip adapted to be fastened to the wall or ceiling and having a grooved outer face, and a second strip adapted to fit in and fill said groove, the cross sectional outlines of the two strips being such that when thus assembled their outer faces merge in a continuous outwardly bulging profile.
